UNITED STATES PATENT OFFICE.

BOYD A. DOTY, OF BUFFALO, NEW YORK, ASSIGNOR TO HARD MANUFACTURING CO.,
OF BUFFALO, NEW YORK.

CRIB OR BED.

1,371,607.

Specification of Letters Patent.

Patented Mar. 15, 1921.

Application filed May 13, 1919. Serial No. 296,787.

To all whom it may concern:

Be it known that I, BOYD A. DOTY, a citizen of the United States, residing at Buffalo, in the county of Erie and State of New York, have invented a new and useful Improvement in Cribs or Beds, of which the following is a specification.

This invention relates more particularly to improvements in children's metal cribs or beds of that kind which have vertically sliding sides or side railings adapted to be retained in an elevated position for confining the child, and to be lowered to facilitate placing the child in or removing it from the crib. In these cribs, which are commonly made with metal end frames having tubular corner posts, the sides slide at their ends on upright guide rods which extend parallel with the corner posts and are supported by brackets or parts attached to and extending laterally from the corner posts or end frames. The supporting or attaching brackets are separately fastened to the end frames or corner posts, usually by external or exposed fastening means or parts of the brackets surrounding the corner posts. Such fastening means, especially in case of the upper brackets, are unsightly, or else if they are of an ornamental form which does not detract from the appearance of the crib, they add materially to its cost of production.

The object of this invention is to provide means of exceedingly simple and inexpensive construction for securing the guide rods to the crib frame, but which nevertheless are of neat appearance and do not necessitate external or exposed fastening means for the upper ends of the guide rods.

40 In the accompanying drawings:

Figure 1 is a side elevation of a child's metal crib or bed embodying the invention.

Fig. 2 is a broken sectional elevation on an enlarged scale of one of the corner posts 45 and the guide rod attached thereto.

Figs. 3 and 4 are sectional plan views thereof on lines 3—3 and 4—4 respectively, Fig. 2.

A and B represent the corner posts of the 50 upright end frames and C one of the sliding side frames or railings of a child's crib or bed. A metal crib is shown in the drawings, in which, as usual, the end frames are connected by a rigid rectangular bottom frame 55 or bed spring D which is suitably secured

to the end frames so as to rigidly connect the frames. The crib frame can, however, be of any other usual or suitable construction. The sides or side railings preferably consist, 60 as usual, of upper and lower horizontal rails d connected by parallel vertical rods and are arranged to slide up and down on vertical guide rods E which are connected at their upper and lower ends to, and are spaced 65 from the end frames or corner posts and pass through guide loops or eyes e at the corners of the side railings.

Each of the vertical guide rods E is attached to the adjacent corner posts of the 70 crib frame as clearly shown in Figs. 2—4. The guide rod is provided at its upper end with a laterally or horizontally extending or bent attaching arm or portion 10, the end or extremity 11 of which is preferably 75 curved or bent upwardly and extends into the tubular corner post through a hole 12 in the inner side thereof. The hole 12 is preferably just large enough to permit the end of the guide rod to be inserted therein 80 and the guide rod when in place practically fills and closes the hole. The guide rod is secured on the corner post by inserting the curved attaching portion at the upper end of the guide rod into the hole 12 while the 85 rod is in an inclined position, as indicated by dotted lines in Fig. 2. The rod is then swung down to a vertical position causing the curved extremity 11 thereof to turn upwardly into the tubular corner post. The 90 guide rod is then secured in this position and prevented from detachment from the corner post by a fastening device at its lower end which prevents the rod from being swung out of the vertical position and thus 95 prevents the disconnection of the upper end of the guide rod except by first releasing its lower end. The lower end of the guide rod is preferably connected to the corner post or end frame by a bracket 13 which is provided with a hole 14 into which the lower end of the guide rod is inserted. The bracket is secured to the corner post or end frame by a screw or fastening device 15 which passes through a hole in the down-bent or depending inner end of the bracket and is screwed into a threaded hole in the corner post or end frame.

The face of the depending inner end of the bracket is preferably curved to fit the ex- 110

ternal surface of the corner post, and a single screw 15 therefore suffices to rigidly fasten the bracket and prevent it from turning or swinging about the screw.

5 The shape or curvature of the upper attaching portion of the guide rod is preferably such that when it is in place in the hole 12 in the corner post the curved extremity 11 thereof, which is located within 10 the corner post, engages the upper edge of the hole 12 and the opposite side of the inner face of the corner post, as shown in Fig. 2, thus preventing either inward or outward movement of the upper end of the guide rod.

15 The upper end of the guide rod is thus held rigidly unless its lower end is released. Nevertheless there are no exposed securing or fastening means for the upper end of the guide rod and no part or device other than 20 the integral bent end of the guide rod itself is employed for securing the upper end of the guide rod to the end frame. Only one bracket and a single screw is required for rigidly fastening the guide rod to the corner post. This is, therefore, a very much simpler and much less expensive construction than those heretofore employed in which the 25 guide rod is secured at its ends in separate brackets separately secured to the corner post or end frame. With such prior constructions, in addition to the separate upper bracket and the means for fastening the same to the corner post or end frame, means are also required for securing the upper and 30 lower ends of the guide rod in the brackets.

35 1 claim as my invention:

1. The combination with a crib frame tube

having a hole in one side and a sliding side member, of a guide rod for said side member, said guide rod having a bent attaching portion at one end which extends through said hole and engages the interior of the tube to secure said end of the rod to the tube, said attaching portion terminating inside of said tube, and securing means for 45 the other end of said rod.

2. The combination with a crib frame tube having a hole in one side, and a sliding side member, of a rod adapted in its normal position to constitute a guide for said sliding side member. said rod having a bent attaching portion extending through said hole and in its normal position terminating within and bearing upon the interior of said tube and movable relatively to said tube for permitting withdrawal of the attaching portion of said rod from the tube, and securing means for the other end of the rod for releasably retaining the rod in said normal position.

3. The combination with a crib frame tube having a hole in one side, of a rod extending parallel with said tube and having a laterally and upwardly bent attaching portion at one end which extends through said hole and engages the interior of the tube to secure said 65 end of the rod to the tube, said attaching portion terminating inside of said tube, and securing means for the other end of the rod.

Witness my hand this 9th day of May, 1919.

BOYD A. DOTY.
